UNITED STATES PATENT OFFICE.

JAMES O'NEIL, OF SAN FRANCISCO, CALIFORNIA.

DESIGN FOR CENTER-PIECE.

Specification forming part of Design No. 7,563, dated July 14, 1874; application filed June 12, 1874.
[Term of Patent 3½ years.]

CASE D.

To all whom it may concern:

Be it known that I, JAMES O'NEIL, of San Francisco, in the county of San Francisco and State of California, have invented or produced a new Design for Center-Pieces; and I do hereby declare that the following is a full, clear, and exact description of the same, reference being had to the annexed photographic illustration, and to the letters marked thereon.

This design consists of a rosette, *a*, from which extend radial arms *b*, every other one of which terminates in a scroll. A small bead or line, *c*, is thrown around these arms, which in turn is surrounded by a net-work, *d*, in relief.

A fluted bead, *e*, edged with scroll-work, surrounds this net-work, upon which are placed daisies *f*. Diamond bands *g*, with beaded

edges, surround the fluted bead *e*, and which terminate at the edge of the shield in shell-work, scroll-work, and the architectural figure *h*.

The edge of this design is of the plain order, except when interrupted by the figure *h*.

Having thus described my invention, what I claim as new, and desire to secure by Letters Patent, is—

The design for a center-piece, as set forth and described.

In witness whereof I have hereunto set my hand and seal.

JAMES O'NEIL. [L. S.]
